Primary Examiner — Susan Bennett Hattan*Assistant Examiner* — Suzanne E Tisdell(74) *Attorney, Agent, or Firm* — Westerman, Hattori, Daniels & Adrian, LLP(57) **CLAIM**

The ornamental design for a grill for automobiles, as shown and described.

DESCRIPTION

FIG. 1: a front view of a grille for automobiles;
FIG. 2: a plan view of the grille for automobiles;
FIG. 3: a left side view of the grille for automobiles; and,
FIG. 4: a front perspective view of the grille for automobiles as seen from the left side.

The broken lines in the drawings illustrate portions of the grill for automobiles that forms no part of the claimed design.
